UNITED STATES PATENT OFFICE.

ERNEST H. BENNETT, OF EAST ORANGE, NEW JERSEY.

DESIGN FOR A RUG.

SPECIFICATION forming part of Design No. 35,084, dated September 10, 1901.

Application filed August 17, 1901. Serial No. 72,449. Term of patent 3½ years.

To all whom it may concern:

Be it known that I, ERNEST H. BENNETT, a citizen of the United States, residing at East Orange, in the State of New Jersey, have invented and produced a certain new and original Design for a Rug, of which the following is a full, clear, and exact description, reference being had to the accompanying drawings, forming a part of this specification.

10 My design is applicable to and intended for the surface ornamentation of woven rugs. In its essentials it consists, as shown in the drawings, of a floral centerpiece A, oval in outline as a whole and composed of a variety leaves and flowers, with a border B of leaf-like figures, forming a substantially rectangular exterior outline and irregular on the interior line. 15

I claim—

The design for a rug, substantially as shown and described.

In testimony whereof I have hereunto affixed my signature this 14th day of August, A. D. 1901.

ERNEST H. BENNETT.
